UNITED STATES PATENT OFFICE.

WILLIAM J. MANHIRE, OF KANSAS CITY, MISSOURI, ASSIGNOR TO COMBUSTION
SPECIALTY COMPANY, OF KANSAS CITY, MISSOURI, A CORPORATION OF MIS-
SOURI.

AUTOMATIC REGULATOR FOR BOILER FURNACES.

1,415,940.

Specification of Letters Patent. Patented May 16, 1922.

Application filed May 27, 1920. Serial No. 384,766.

To all whom it may concern:

Be it known that I, WILLIAM J. MANHIRE, a citizen of the United States, and resident of Kansas City, county of Jackson, and 5 State of Missouri, have invented a certain new and useful Improvement in Automatic Regulators for Boiler Furnaces, of which the following is a complete specification.

This invention relates to fan engine regulators, and more especially to mechanisms for use with fan engines for circulating air through the fuel bed of a boiler furnace, the object being to produce an automatic mechanism for gradually increasing or decreasing 15 the supply of air to the grate as the steam pressure of the boiler falls or rises, and thus obtain approximately uniform generation of heat by the furnace between grate cleaning and fuel replenishing periods.

20 With this general object in view, the invention consists in certain novel and useful features of construction and combinations of parts as hereinafter described and claimed; and in order that it may be fully understood 25 reference is to be had to the accompanying drawing, in which:—

Figure 1 is a top plan view of a fan engine regulator embodying the invention.

Figure 2 is a side view of the same showing certain parts in central vertical section to more clearly illustrate the invention.

In the said drawing, 1 indicates a suitably supported base plate provided with a circular cavity 2 in its upper side covered by 35 a diaphragm 3, and mounted upon said plate and covering the diaphragm is a disc 4 secured rigidly to the plate by a series of bolts 5. The disc is provided with a shallow chamber 6 in its lower side corresponding 40 in location to the diaphragm and of the same diameter, and said chamber is formed with a deepened portion 7 communicating at its center with a vertical opening 8 through which projects a knife edged plunger 9 pro- 45 vided at its lower end with an enlargement or head 10 fitting in the deepened portion 7 of said chamber and resting on the dia- phragm and adapted when the latter is pressed upwardly or expanded, to move up- 50 ward, this action of the diaphragm being accomplished by steam introduced into said chamber 2 through a pipe 11 connected to the boiler of the furnace, not shown.

Extending between a pair of standards 55 and fulcrumed thereon as at 12 is a lever 13,

the same being disposed vertically over the plunger 9 so that when the latter is pushed upward the lever will be raised, and underlying the lever and mounted on the disc 4 is a pair of adjustable stops 14 and 15 for 60 limiting pivotal movement of the lever.

Pivots suspended from the outer end of the lever is a rod 16, on which are removably secured weights 17 for the purpose of holding the lever depressed upon the stop 15 65 until a predetermined steam pressure is applied against the under side of the dia- phragm, and adjustably carried by the lever is a poise 18, and a slide 19 provided with a cavity 20 in its upper side containing a 70 ball 21, a set screw 22 being employed to secure the slide at the desired point of adjustment on the lever.

A standard 23 is mounted on the base plate for the support of a pipe 24 for con- 75 ducting steam from the boiler to the fan engine, not shown, and said pipe is equipped with a valve 25 having the stem 26 of the valve proper pivotally attached to a lever 27 fulcrumed at 28 on an arm of the casing 80 of said valve. A slide 29 is mounted on said lever and secured at the desired point of adjustment by set screw 30, and pivotally de- pending from said slide is a rod 31, carry- 85 ing a cage consisting of discs 32 and 33 con- nected by rods 34, and mounted on disc 33 regulating weights 36 provided with central openings 37 of different diameter, the diam- eters of the weights 36 to the topmost weight. A lift pin 38 fits slidably in the 90 disc 33 and normally rests on the ball 21, being provided with a cavity 39 in its lower end for receiving the upper portion of said ball, and said pin is reduced to form shoul- ders 40 of diminishing diameter upward, 95 the arrangement being such that when the lever 13 is raised, sufficiently, the upper end or shoulder of the pin 40 of said pin suc- cessively raise the remaining weights, be- ginning with the second one from the top, 100 then the third one and so on until all of the weights have been lifted. When all of the weights 36 are carried by the lever 27, the valve 25 is opened to its fullest extent, and as said weights 36 are successively removed 105 from support by lever 27, the valve 25 is gradually closed, that is to say, as the steam pressure on the diaphragm increases, the valve 25 gradually closes and thus cuts down 110 the supply of steam to the fan engine, and

proportionately reduces the volume of air supplied by said fan engine to the grate of the furnace.

5 A rod 41 is pivotally suspended from the inner end of lever 27 and carries removable weights 42 complementary to the weight of the cage at the outer end of the lever, and to guard against spasmodic operation of lever 27, a dash pot 43 is mounted upon an 10 arm 44 of standard 23, the plunger 45 of the dash pot having its stem 46 pivotally connected to the said lever 27.

From the foregoing it will be apparent that as the stem pressure on the diaphragm 15 fluctuates, the lever 13 will be operated and through the connections and mechanism described will effect slow and gradual opening and closing movements of the valve 25, and thus regulate the volume of air supplied to 20 the grate by the fan engine, it being apparent that by reason of the fact that the lift pin 38 picks up the weights 36, one at a time, the changes in the quantity of air supplied by the fan engine to the grate will be soft 25 and gradual as distinguished from spasmodic or violent changes. It will of course be understood that the changes in boiler pressure will be due to the fact that the accumulation of ashes on the grate effects a 30 proportionate increase in the resistance to the passage of air through the grate and that the increase of air is necessary to compensate for this increased resistance.

When the regulator is in operation there 35 is a constant but slight fluctuation in the movement of lever 13 due to slight fluctuation in the boiler pressure, and this can be noticed, particularly in very slight fluctuations, as the topmost weight 36 can be seen to rise slightly off the underlying weight 40 and then move downward again. If the fluctuations are somewhat greater the topmost weight will rise and then be followed upward by the underlying weight, and perhaps by one or more additional weights, 45 said weights dropping back in the reverse order as the pressure is diminished, and these vary the speed of the fan engine as herein-after stated. Where the range or boiler 50 pressure cannot be permitted to fluctuate the amount necessary to lift and lower all of the weights 36, as shown, it is forced to accommodate the mechanism to such condition without changing the value of the 55 weights themselves, by shifting the cage inward on lever 27 and the poise 18 outward on lever 13.

I claim:

60 1. The combination of a pipe for supplying fluid under pressure to a fan engine, a controlling valve for said pipe, a counter-balanced lever for operating said valve, a series of weights carried by said lever for 65 conjointly holding the valve fully open, and means actuated by fluid under pressure be-

yond a predetermined degree, for movement in one direction to successively relieve the lever of said weights to permit it to operate and impart closing movement to said valve; said means under decreasing pressure of the 70 fluid, reverses its movement to successively reimpose said weights upon said lever.

2. The combination of a pipe for supplying fluid under pressure to a fan engine, a controlling valve for said pipe, a counter- 75 balanced lever for operating said valve, a series of weights carried by said lever for conjointly holding the valve fully open, means actuated by fluid under pressure beyond a predetermined degree, for movement 80 in one direction to successively relieve the lever of said weights to permit it to operate and impart closing movements to said valve; said means under decreasing pressure of said fluid, reversing its movement to successively 85 reimpose said weights upon said lever, and means to prevent spasmodic operation of said lever.

3. The combination of a pipe for supplying fluid under pressure to a fan engine, a 90 controlling valve for said pipe, a counter-balanced lever for operating the valve, a series of weights carried by said lever for conjointly holding the valve fully open, means for successively lifting or lowering 95 said weights, and means actuated by fluid under pressure beyond a predetermined degree or falling toward such degree, for respectively lifting or lowering the first named means.

100 4. The combination of a pipe for supplying fluid under pressure to a fan engine, a controlling valve for said pipe, a counter-balanced lever for operating said valve, a series of weights carried by said lever for 105 conjointly holding the valve fully open, means for successively lifting or lowering said weights, a second lever supporting said first named means, and means actuated by fluid under pressure rising beyond a pre- 110 determined degree or falling toward such degree, for respectively lifting or lowering said first-named means.

5. The combination of a pipe for supplying fluid under pressure to a fan engine, a 115 controlling valve for said pipe, a counter-balanced lever for operating said valve, a series of weights carried by said lever for conjointly holding the valve fully open, means for successively lifting or lowering 120 said weights, a second lever supporting said first-named means, a diaphragm for operating said second lever in one direction, and means for supplying fluid under pressure to expand said diaphragm 125 to operate said lever to cause said first-named means to relieve the first-named lever of weight.

6. The combination of a pipe for supplying fluid under pressure, to a fan engine, a 130

controlling valve for such pipe, a lever for operating the valve, a series of weights adjustably carried by said lever for conjointly holding the valve fully open, a second lever, 5 means carried by the second lever for relieving the first lever of or reimposing said weights successively on said first-named lever, and adjustable means for changing the load on said second lever.

10 7. The combination of a pipe for supplying fluid under pressure to a fan engine, a controlling valve for such pipe, a lever for operating the valve, a series of weights adjustably carried by said lever for conjointly 15 holding the valves fully open, a second lever, means carried by the second lever for relieving the first lever of or reimposing said weights successively on said first-named lever, a diaphragm, means carried thereby 20 for engaging the second lever, and means for applying fluid under pressure to expand the diaphragm to cause the lever-engaging means to operate the second lever to gradually relieve the first-named lever of weight 25 thereon or permit the diaphragm to contract

to gradually reimpose weights upon the first-named lever.

8. The combination of a lever, a pipe for supplying fluid under pressure, a valve actuated by said lever for controlling said pipe, 30 a cage suspended from said lever, a series of superposed weights carried by said cage and provided with holes of diameter decreasing from the bottom weight to the top weight, a pin having reduced portions corresponding 35 to said weights to form a corresponding number of shoulders for respectively lifting said weights one at a time, beginning with the topmost thereof, or for successively lowering said weights one at a time beginning 40 with the undermost thereof, and means actuated by fluid pressure beyond a predetermined degree, for imparting movement to said pin to lift one or more of said weights and adapted under pressure falling toward 45 said predetermined degree, to reverse the movement of said weight lifting means.

In testimony whereof I hereunto affix my signature.

WM. J. MANHIRE.
